(57) **CLAIM**

The ornamental design for a powered angle grinder tool with rear mounted motor, as shown and described.

DESCRIPTION

FIG. 1 is a perspective view of a powered angle grinder tool with rear mounted motor according to the present invention; FIG. 2 is a front view of the powered angle grinder tool with rear mounted motor shown in FIG. 1;

FIG. 3 is a left side view of the powered angle grinder tool with rear mounted motor shown in FIG. 1;

FIG. 4 is a rear view of the powered angle grinder tool with rear mounted motor shown in FIG. 1;

FIG. 5 is a right side view of the powered angle grinder tool with rear mounted motor shown in FIG. 1;

FIG. 6 is a top view of the powered angle grinder tool with rear mounted motor shown in FIG. 1; and,

FIG. 7 is a bottom view of the powered angle grinder tool with rear mounted motor shown in FIG. 1.

Structure shown in broken lines in FIGS. 1-7 form no part of the claimed design.
